**FIRING POSITION INDICATOR FOR USE IN
ADJUSTING VALVE CLEARANCES**

Leonard E. Berry, Corcoran, Calif.

Application October 8, 1953, Serial No. 384,925

3 Claims. (Cl. 116—124)

The present invention relates to new and useful improvements in tools for use in adjusting valve clearances of engines and more particularly to an indicator having means for connecting to the cam shaft to show successively the firing position of the several pistons in order to accurately adjust the clearance for the valves.

An important object of the invention is to provide a pointer for the indicator associated with a dial marked with the position of each valve and equipping the pointer with an actuating gear for connection with the cam shaft in place of and after removal of the engine distributor.

A further object is to provide a device of this character of simple and practical construction, which is efficient and reliable in operation, relatively inexpensive to manufacture and otherwise well adapted for the purpose for which the same is intended.

These together with other objects and advantages which will become subsequently apparent reside in the details of construction and operation as more fully hereinafter described and claimed, reference being had to the accompanying drawings forming a part hereof, wherein like numerals refer to like parts throughout and in which:

Figure 1 is a perspective view;

Figure 2 is a vertical sectional view;

Figure 3 is a top plan view showing the indicator mounted on the engine; and

Figure 4 is a front elevational view thereof with the distributor housing broken away and shown in section.

Referring now to the drawing in detail, wherein for the purpose of illustration I have disclosed a preferred embodiment of my invention, the numeral 5 designates a shaft having a worm gear 6 secured at one end.

A pointer 7 is secured to the other end of the shaft and overlies a dial 8 which is formed at its underside with a sleeve 9 and which is mounted on the shaft for independent turning movement relative to the shaft. The dial and sleeve are held in position adjacent the pointer by means of collars 10 and 11 secured to the shaft respectively above the dial and below the sleeve. The upper surface of the dial is marked with radial lines 12 adjacent to which are numbers 13 representing the intake and exhaust valves of an engine in their closed position in the successive firing order of the pistons of the engine.

In the operation of the device, the engine distributor (not shown) is removed from the tubular distributor shaft housing 16 of the engine 17 and the shaft 5 mounted in the housing and with the worm gear 6 meshing with the

2

worm 18 of the cam shaft for turning shaft 5 in the same manner as that of the distributor shaft. Lower collar 11 is tapered, as shown at 14, to hold the shaft 5 tightly in position in the distributor shaft housing of the engine.

The engine crank shaft is then turned until number 1 piston is in firing position, as indicated by the usual timing mark 19 and stationary timing pin 20. Dial 8 is then turned and locked by the distributor locking bolt 10 15, in position with the pointer 7 alined with the valve on the dial which corresponds with said piston, whereupon said valve may be accurately adjusted. The crankshaft is then progressively turned to indicate the closed position of the remaining valves for successively adjusting the same.

What is claimed as new is as follows:

1. A piston position indicator comprising in combination, an engine cam shaft having a gear secured thereto, an indicator shaft having a gear at one end engaging the first named gear for operatively connecting said shafts to each other, a pointer at the other end of the indicator shaft for swinging about the axis of the latter by the turning of the cam shaft, a dial supported on the indicator shaft in indicating position by the pointer, said dial being independently rotatable on the indicator shaft, and means locking the dial in rotatably adjusted position to a stationary part of the engine.

2. A piston position indicator comprising in combination, an engine block having a cam shaft therein and said block also having an opening adjacent a gear on the cam shaft, an indicator shaft having a tapered collar closely fitted in said opening to support the indicator shaft centered in the opening, a gear at the lower end of the indicator shaft engaging the first named gear, a pointer secured to the upper end of the indicator shaft for swinging about the axis of the latter by the turning of the cam shaft, a dial mounted on the indicator shaft in indicating position by the pointer, said dial being independently rotatable on the indicator shaft, and means locking the dial in rotatably adjusted position to a stationary part of the engine.

3. A piston position indicator comprising in combination, an engine block having a tubular distributor shaft housing and a cam shaft driven gear in the housing, an indicator shaft mounted in the housing after removal of the distributor therefrom, a gear at the inner end of the indicator shaft engaging said first named gear, a dial supported in rotatably adjusted position by the indicator shaft, and a pointer attached to the outer end of the indicator shaft and supported in indicating position with respect to the dial.
